PACKAGING CONTAINER FOR COMESTIBLES OR THE LIKE

Roy W. Bloch, Northbrook, Ill., assignor to Ekco
Products, Inc., Wheeling, Ill.

Filed Oct. 28, 1970, Ser. No. 25,690

Term of patent 14 years

Int. Cl. D9—03

U.S. Cl. D9—187

FIG. 1

FIG. 2

FIG. 3

FIG. 4

FIG. 1 is a top plan view of a packaging container for comestibles or the like showing my new design.

FIG. 2 is a front or rear elevational view partially cut-away thereof, taken along line 2—2 of FIG. 1.

FIG. 3 is a right or left end elevational view thereof.

FIG. 4 is an enlarged fragmentary perspective view thereof.

I claim:

The ornamental design for a packaging container for comestibles or the like, as shown.
